UNITED STATES PATENT OFFICE.

SOLOMON M. CUTTER, OF HARTFORD, CONNECTICUT, ASSIGNOR TO CAPEWELL HORSE NAIL COMPANY, OF HARTFORD, CONNECTICUT, A CORPORATION OF CONNECTICUT.

MANUFACTURE OF HORSE NAILS.

Application filed January 20, 1917. Serial No. 143,436.

To all whom it may concern:

Be it known that I, SOLOMON M. CUTTER, a United States citizen, residing in Hartford, Connecticut, have invented the following described Improvements in the Manufacture of Horse Nails.

The invention provides a simple and economical means of producing heads of improved structure and superior finish on horse-nails and other nails, and consists in the herein described method of upsetting a partially formed nail blank whereby the corners and edges of the rudimentary nail are turned or crowded inwardly into the body of the head and under conditions which permit the final shaping of the head without the formation of fins and without disturbing the original lateral surface of the blank which may be the same surface as the stock from which the blank was made. In the drawings forming part hereof,

Fig. 1 represents a nail-blank with a rudimentary head in its relation to the die-cavity in which it is finished;

Fig. 2 an edge view of the same blank in the same die-cavity;

Figs. 3 and 4 represent similar views with the first heading tool in the position it assumes at the completion of its heading stroke;

Figs. 5 and 6 are similar views with the second and final heading tool in the position it assumes at the end of its stroke;

Fig. 7 illustrates, in larger scale and more or less diagrammatically, the action of the first heading tool upon the blank; and

Fig. 8 shows the finished nail-head.

The nail-blank shown in Figs. 1 and 2 will be understood to be made of steel wire stock or other metal capable of being worked cold, and in the case of a horse-nail, is formed by die-rolling a wire of rectangular cross-section into a so-called string-nail, or strip of connected nail-blanks which are subsequently severed into separate blanks and pointed as indicated in the drawings. Such a blank has a rudimentary head of substantially the same cross-sectional shape as the original wire stock, but longer and narrower than the finished head and its top surface is irregular and commonly shows the mark of the shear by which it was severed from the string. It is first inserted in a sectional die block composed of the parts 1 and 2, which will be understood to be firmly seated in an

appropriate solid bed, not shown in the drawings. The die block provides, in or between its parts, a groove or recess 3, which is for the entry of the heading tools; and the die cavity proper, which opens into this recess, is shaped according to the desired finished form of the lower part only, of the nail-head, including also the immediately adjoining upper part of the shank or blade of the nail. When the blank is in place in this cavity, the upper part of the head projects into the recess 3, being laterally unconfined by the die as will be noted, and the opposite end projects beyond the opposite side of the die blocks, in which projecting relation that end may have already been subject to the pointing and trimming operations. The lower shoulders of the rudimentary head engage or rest upon the sloping faces of the nail-head cavity about as indicated in Figs. 1 and 2.

The first heading tool, marked 4 in the drawings and understood to be mounted on a reciprocating plunger and appropriately guided, enters the recess 3 and therein engages the projecting head of the blank by its striking face which is concaved or cupped as shown in Figs. 3 and 4, the concavity being oblong in the case of a horse nail-head. The upsetting stroke of this tool is limited so that it advances upon the blank no further than necessary to shape the upper part of the head and cause its lower part to fill out and more or less completely occupy the lower part or all of the tapered head cavity 5, which as stated conforms to the lower part of the finished nail-head. The tool does not approximate a contact with the bottom of the recess 3, and Figs. 3, 4 and 7 indicate in a general way the extent of this initial upset, it being understood of course, that some variation arises from variation of the amount of metal in the head. The upper rough-cut end of the nail head is thus compacted and domed by the concavity of the heading tool and the corners and edges thereof are turned or folded inward towards the axis of the nail, while the intermediate part 6 of the head blank,—the part which intervenes between the die-cavity of the heading tool and the die-cavity of the block—is distorted and slightly swollen by the effect of the stroke and according to the displacement of the metal above it. By appropriately varying the limit of the stroke

of the tool or the metal in the blank head, the extent of such lateral bulging of the blank is subjected to control and is easily restricted to the dimensions of the finished nail-head. It will be observed that the nail-head in this condition still retains its original surface or skin except at the very top where the corners have been crowded inward in producing the domed top.

10 After the withdrawal of the heading tool 4, the rounded and slightly bulged nail-head is subjected to the stroke of a second heading tool, marked 7 in Figs. 5 and 6. The shape of this tool, as will be plain from the 15 drawings, represents the intended shape for the top surface or surfaces of the nail head. The said tool, being appropriately mounted for the purpose, fits the recess 3 snugly and advances on the blank far enough to im- 20 part its own shape thereto, at the same time further swelling the head into full contact with the walls of the die-cavity, and giving the part 6 the thickness of the recess 3 as shown in Fig. 6, and also increasing its 25 width a desired amount. The edges thus formed on the part 6, are formed by unob- structed bulging into the recess 3 and are therefore slightly curved as indicated more clearly in Fig. 8, but such curvature is not 30 conspicuous in the nail itself. Neither heading tool approaches closely enough to the bot- 35 tom of the recess 3 to develop fins on the part 6 and consequently the nail head is finished when the second tool withdraws and requires merely to be cleaned to be ready

for shipment. It retains the smooth sur- 40 face or skin of the original wire stock on its sides, which obviously remains unbroken and is simply stretched to accommodate the material folded in by the upsetting action. It follows that the only surface irregularities in the arrangement of the original fibres of the metal are confined to an area well within the edges defining the top of the nail- 45 head, and at this point such irregularities are not therefore thereafter subjected to influences which would make them apparent or objectionable, while the objects stated are attained by no greater number of head- forming steps than are now generally em- 50 ployed.

Claim:

The method of producing nail-heads on horse-nails, which consists in holding a nail- 55 blank head in a die-cavity shaped to conform with the form of the lower part of the de- sired nail-head, upsetting said blank by a cupped tool adapted to fold the corners thereof inwardly and while leaving the in- termediate portion of the head free to swell 60 or bulge laterally under the effect of such heading tool and thereafter upsetting the said nail-blank head with a finishing heading tool while retaining said intermediate portion of the nail-head unobstructed as to 65 bulging in the direction of its width.

In testimony whereof, I have signed this specification.

SOLOMON M. CUTTER.
